EASEL

Stephen L. Dearing, Palmyra, Mo.

Application April 6, 1938, Serial No. 200,484

4 Claims. (Cl. 40—125)

This invention relates to a sign easel and it consists in the constructions, arrangements and combinations herein described and claimed.

It is an object of the invention to provide a sign easel embodying a novel mounting of prop leg which is automatically locked in either of its collapsed or set-up positions.

It is also an object of the invention to provide a novel sign supporting panel so constructed as 10 to accommodate and rigidly secure either diamond or square shaped signs.

It is a still further object to provide an easel which is of extreme simplicity in construction and operation, of light weight and readily set up 15 or collapsed with a minimum of effort.

Additional objects, advantages and features of invention will be apparent from the following description and accompanying drawing, wherein

20 Figure 1 is a front elevation of the easel, set up. Figure 2 is a vertical section thereof.

Figure 3 is a view similar to Figure 2, indicating the various movements of the prop leg, in dotted lines.

25 Figure 4 is a fragmentary rear elevation, illustrating the mounting of the prop leg.

Figure 5 is a cross section on the line 5—5 of Fig. 4.

Figure 6 is a sectional view illustrating a sign 30 locking element.

Figure 7 is a sectional view illustrating a sign supporting member as embodied in the lower portion of the easel.

Figure 8 is a fragmentary view of a modified 35 form of sign fastener.

There is illustrated an easel generally indicated at 10, comprising a pair of front leg members 11 arranged in an upwardly inclined direction with respect to each other, thus spacing the 40 bases of the legs a substantial distance apart, affording ample support of the easel as will be apparent as the description proceeds.

The upper ends of the legs are connected by a top panel 12, and intermediate the length of the 45 legs 11 a lower panel 13 is secured.

Obviously, the easel may be formed from any suitable material, but in the present instance, the easel will be described as an easel for support of road signs, and since it will be subjected to 50 exposure of the weather, the device will be constructed from iron straps and sheet metal.

The top panel 12 has rearwardly directed ears 14 which may be separately formed and secured to the panel or may be formed as integral portions of the panel by stamping operations. The

ears 14 are apertured and the outer peripheral edge of the ears are dished inwardly toward each other, as at 15.

A bail 16 is provided formed from a single piece of spring steel rod of proper gauge, and as 5 may be seen in Figure 1, is substantially U-shaped, the leg portions 17 of which are bent at right angles, in opposite directions, to form pivot pins 18. A pin 19 is engaged in respective apertures of the ears 14 and as clearly shown 10 in Figure 4, the dished portion 15 lies inwardly of the legs 17. The straight portion 19 of the bail pivotally mounts a yoke 20 composed of a pair of parallel strap members 21, the outer ends of which are bent inwardly toward each other 15 and receive a prop leg 22 therebetween, the strap members being riveted or otherwise secured to the leg as at 23. The upper ends of the strap members 21 have a notched end 24 for a purpose presently to be explained.

The lower panel 13 has a pair of rearwardly struck ears 25 pivotally mounting brace links 26, the links converging inwardly to lie upon opposite sides of the prop leg 22 for pivotal securing thereto, as at 27.

The upper panel 12 will include means for holding a sign securely in place, and in the present instance, there is shown a dog 28. The dog has an inclined lip 29, inwardly of which there is a notch 30 and downwardly extended a tail 30 piece 31. The tail piece is slidably mounted in a pair of ears 32, struck outwardly at right angles to the panel. The lower end of the tail piece has secured thereon a washer 33 and between this washer and the lowermost ear 32, there is 35 a helical spring 34. By this construction it will be seen that the dog will be drawn downwardly in the slot 35 formed in the upper edge of the panel. The dog 28 will occupy a position in the slot with the notch 30 presented downwardly so 40 as to engage a sign when drawn down by the spring 32.

The lower panel 13 will include outwardly struck flanges 36 at respective end portions, the flanges being presented upwardly in opposition 45 to the lip 29 of the dog.

Reference is now made to Figure 3 of the drawing, and in order to set up the easel for support of a sign, it will be necessary to move the prop leg 22 from its collapsed position shown in solid 50 lines to its final position shown by dotted lines D. The first movement of the leg 22 is indicated at A, the second position at B; a third position at C, and the final position at D, and it will be noted that these movements are permitted by 55

reason of the pivotal connection of the leg portions 17 of the bail, and that in the final set-up position of the leg the notch 24 receives the lower edge of the panel 12 therein. The leg 22 5 is thus disposed at an angle suitable for support of the easel.

It should be noted that the dished portions 15 lie in the path of the legs 17 and therefore as the bail is swung either to its upper or lower 10 positions, the legs 17 must be sprung inwardly toward each other in order to permit the legs 17 to pass, and after such operation the bail 16 will be securely yet releasably held in position to either side of the dished portion of the ears.

15 In movement of the prop leg to either its collapsed or set up position, the bail 16 traverses an arc of approximately 180 degrees, while the braces 26 swing in an arc of approximately 50 degrees.

20 With the easel set up, and it is desired to secure a square sign thereon, the sign is positioned so as to align the upper aperture 37 of the sign with the dog 28. The aperture 37 is located in the vertical center of the sign, as seen in Figure 25 1, spaced from the upper edge so as to partly register with the dog 28, and by exerting an upward pressure upon the sign, the dog will be raised against the tension of the spring 32 until the lower edge of the sign clears the upper edge of 30 the channel 36. When the sign is released the sign will be seated in the channel with the dog pressing downwardly upon the upper edge of the sign.

35 The securing of a diamond shaped sign is similar, although in this instance, the sign S' will be positioned so that a pair of edges 38 of the sign engage the channels 36. The distance between the channels 36 and dog 28 are so proportioned that the square signs and the diamond 40 signs, which are standard, are so punched that the top hole of either coincide at the position of the dog 28.

If desired, the channels 36 may be replaced by 45 a single rigid dog 39 so placed as to engage the lower aperture 40 of the sign.

Obviously, a single panel could be employed, replacing those indicated as 12 and 13, which could be fabricated or otherwise.

While I have shown and described a preferred construction, this is by way of illustration only, 5 and I consider as my own all such modifications in structure as fairly fall within the scope of the appended claims.

I claim:

1. An easel for support of signs and the like 10 comprising a pair of front leg members, upper and lower panels connecting the legs, ears upon the panels, brace links swingably mounted in the ears of the lower panel, a bail swingably mounted in the ears of the upper panel, a prop leg swing- 15 ably mounted on the bail, said bail being swingable through an arc of approximately 180 degrees and the upper end of said prop leg having a notched portion for engaging the lower edge of the upper panel when in erected position. 20

2. The structure of claim 1 in which the ears of the upper panel include means cooperable with the bail for releasably holding the bail in either position of its swinging movements.

3. The structure of claim 1 in which the up- 25 per and lower panels include means for attachment of a sign.

4. An easel for support of signs and the like comprising a pair of front leg members, upper and lower transversely extended panels connect- 30 ing the legs, ears upon the rear faces of the panels, a pair of brace links swingably mounted in the ears of the lower panel, said links converging rearwardly, a prop leg interposed between the ends of brace links and pivotally connected there- 35 to, a bail swingably mounted in the ears of the top panel and connected to the prop leg, said ears having dished portions in the path of travel of the legs of the bail whereby to laterally flex said legs and said prop leg having a forked upper exten- 40 sion, each of the extensions having a notched end adapted to engage the lower edge of the upper panel in the set-up position of the easel. 45
